(57) **CLAIM**

The ornamental design for a pole-mountable camera support structure, as shown and described.

DESCRIPTION

FIG. 1 is a front perspective view of a first embodiment of a pole-mountable camera support structure, showing our design;

FIG. 2 is a front view thereof;

FIG. 3 is a rear view thereof;

FIG. 4 is a side view thereof;

FIG. 5 is an opposing side view thereof;

FIG. 6 is a bottom view thereof;

FIG. 7 is a top view thereof;

FIG. 8 is a front perspective environmental view thereof;

FIG. 9 is a front perspective view of a second embodiment of a pole-mountable camera support structure, showing our design;

FIG. 10 is a front view thereof;

FIG. 11 is a rear view thereof;

FIG. 12 is a side view thereof;

FIG. 13 is an opposing side view thereof;

FIG. 14 is a bottom view thereof;

FIG. 15 is a top view thereof; and,

FIG. 16 is a front perspective environmental view thereof.

The broken lines in the drawings depict environmental structure and form no part of the claimed design. The stippling patterns shown in FIGS. 9-16 indicate components that are the same color. The color indicated by the stippling patterns may be any color that is the same for each component including the stippling patterns.
